UNITED STATES PATENT OFFICE.

CHARLES C. COLBERT AND GEORGE E. PRESTON, OF ELKHART, INDIANA, ASSIGNEES TO
AMERICAN COATING MILLS, OF ELKHART, INDIANA, A CORPORATION OF INDIANA.

DRYING METHOD.

Original application filed October 3, 1923, Serial No. 666,268. Divided and this application filed December 1, 1924. Serial No. 753,163.

To all whom it may concern:

Be it known that we, CHARLES C. COLBERT and GEORGE E. PRESTON, citizens of the United States, and residents of Elkhart, 5 in the county of Elkhart and State of Indiana, have invented an Improvement in Drying Methods, of which the following is a specification.

The present invention is intended to provide 10 a method for conducting a drying operation such as hereinafter indicated in an advantageous manner with respect to the material undergoing treatment, as well as with regard to such consideration as economy and rapidity of operation.

The invention will be readily understood by reference to one practicable form of apparatus for practicing such method, shown in the annexed drawings.

20 In said drawings:

Figs. 1 and 2 collectively represent a longitudinal vertical section of a drying room incorporating the illustrative apparatus, Fig. 1 showing the first half and Fig. 2 25 showing the succeeding half thereof. These views are partly diagrammatic, omitting many mechanical details.

Fig. 3 is a cross section.

Fig. 4 is a side view of a portion of conveying means.

Fig. 5 is a cross section on the line 5—5 of Fig. 4.

Reference is made to application Serial No. 666,268, filed October 3, 1923 of which 35 this application is a division, for a fuller disclosure and description of the apparatus selected for illustration, and which is herein described in connection with a process of drying coated paper board.

40 A continuous web of coated paper board is designated in the drawings by the numeral 1. A large quantity of the continuous board, accumulated in undulating formation or in a succession of open folds, is exposed to drying treatment in the illustrative apparatus, which is shown incorporated in a drying room 2. The drying process may progress as the board moves along or through the room, while the freshly coated 45 board is drawn into the receiving end of the room and the dried board is withdrawn from the other end for finishing the coated surface of the board and subdividing or reeling the finished product.

Contact with the coated surface of the 55 board should be avoided until after it is substantially dry. In this instance, board having a liquid coating applied to a selected surface runs with its coated side uppermost into and through the drying room, in which 60 it is supported from its under or uncoated side.

In Fig. 1, the board is shown running into the receiving end of the drying room and being hung up in festoons on transverse supports which in this instance are provided by so-called sticks. Such sticks are indicated at 5 in Figs. 3, 4 and 5. These sticks preferably consist of round wooden poles having their ends flattened to rest on supporting or conveying means without tendency to turn or roll. They should be of sufficient diameter to provide ample supports from which the board may hang without sharp bending. In said application Serial 75 No. 666,268, means are shown for providing supports either by single sticks or pairs of sticks.

The sticks 5 are brought under the in- 80 feeding board at appropriate intervals of time to allow desired lengths of the board to hand between the successively presented sticks. This may be accomplished by elevating means 6 consisting of a pair of endless chains arranged at opposite sides of the 85 board and having suitably spaced lugs for engaging and forwarding the sticks. Said elevating chains pick up the sticks from curved guides 8 arranged coaxially with the lower sprocket wheels of the chains, and 90 into which guides the sticks are successively delivered by a conveyor 9 as explained in said application Ser. No. 666,268.

The elevating chains deliver the sticks 95 with the hung-up board to conveying means represented by successive sections or sets of chains 10, 11, 12, 13, 14, 15, 16, 17. It will be understood that each set comprises a pair of parallel endless chains, spaced apart 100 appropriately to support the ends of the sticks while allowing the festoons of board to hang between the chains. The successive sets or pairs of said endless chains 10, 11, 12, 13, 14, 15, 16, 17, successively carry the sticks with the hanging board, the sticks being transferred from one set of chains to another. These successively arranged 105 sets of carrier chains run at different speeds

as presently to be described for changing the spacing of the sticks, with accompanying contraction or expansion of the festoons of board carried thereby.

5 By running the first pair of carrier chains 10 at an appropriate speed in relation to the elevating chains 6, the sticks carrying the hung-up board are placed upon said chains 10 at desired intervals apart, preferably at 10 fairly wide intervals so as to carry the festoons of board in comparatively distended condition for an initial drying treatment.

In this instance, the chains 11 to which the sticks are delivered by the chains 10 run 15 at a somewhat slower speed than the preceding chains, thereby receiving the sticks at closer intervals and contracting the festoons; so that a greater quantity of board, accumulated in closer formation, is submitted to 20 drying action in the region of the room traversed by said carrier chains 11.

From the relatively slow running chains 11, the sticks carrying the festoons of board are transferred to the chains 12 which run 25 at a relatively fast speed so as to take the sticks at wide intervals apart and thereby spread out or expand the festoons.

The succeeding chains 13 run at a relatively slow speed for again spacing the 30 sticks at closer intervals and narrowing the festoons. So on through the conveying system, the festoons are carried in alternately expanded and contracted condition, and at varying rates of speed; the sections 12, 14 35 and 16 of the conveying system running at relatively fast speed and the alternating sections 11, 13, 15 and 17 running at relatively slow speed.

As the drying process progresses, it is desirable to reform the festoons in order to 40 change the points of suspension of the board and expose the board differently to the drying medium in the room. For this purpose the board may be shifted longitudinally of 45 its supports by training the board over one or more overhead rollers such as indicated at 18, 19 and 20. These rollers are preferably associated with the fast running sections 12, 14 and 16 of the conveyor system.

50 One of said fast running conveyor sections with an overhead shifting roller is shown in Fig. 3, from which it will be seen that the board trained over the roller 18 is withdrawn from the successively advancing 55 sticks 5 and is re-engaged by said sticks beyond the roller at different points from those previously engaged by the respective sticks. Thus the points of suspension of the board are automatically changed. The said overhead roller 18 is power driven at appropriate speed for withdrawing the board from the sticks and effecting a desired lineal advancement of the board relative to the sticks.

60 To maintain desired spacing and correct

transverse alignment of the sticks on the fast running carrier chains 12, 14 and 16, as well as to prevent dislocation of the sticks during shifting of the board relative to its supports, said chains are provided as shown in Fig. 4 with stick-engaging lugs 21, and certain retarding devices are arranged to resist movement of the sticks and thus maintain them in engagement with said lugs. The specific means shown in Fig. 4 is as follows:

70 Rails 22 having inclined or beveled front ends 23 are arranged beside said carrier chains and rise gradually above the level thereof but not above the projections of the chain lugs 22. Above these rails are hanging bars 24 connected by bolt and slot connections 25 to suitable hangers, permitting said bars to be raised. A stick 5 transferred from the slow running chains 11 to the fast

80 running chains 12 rides up the beveled ends 23 of the rails 22 and against the under beveled ends 27 of the upper bars 24. This causes the stick to pause until its ends are engaged by an opposite pair of the chain lugs 22 on said fast running chains 12.

85 These chain lugs then push the stick between the rails 22 and upper bars 24, the latter being elevated by the stick. Said upper bars may have their under surfaces recessed at 28 to relieve the sticks of the weight of said 90 bars. Before passing out from between the rails 22 and upper bars, the stick again engages the upper bars 29 and is forced out between the rails and the under surfaces of the upper bars bearing on the stick. Thus

95 the stick resists dislocation by the pull of the hanging board as it is drawn past the stick over the overhead roller, and correct transverse alignment of the sticks on the 100 parallel chains is maintained. After passing under the overhead roller and to position for re-engagement of the board, the stick may be caused to ride over inclined 105 obstructors 30, thus insuring its alignment by maintaining it against the chain lugs 21.

110 It will be understood that each board shifting section of the conveying system is equipped with means of the character just described.

115 From the foregoing description, it will be seen that the coated board hanging in festoons or folds is conveyed through the drying room by a succession of conveying means running at alternate rates of speed, so as alternately to contract and spread out the festoons to drying action; while the conveyance of the board in this manner is accompanied by one or more shifting of the board to change its points of suspension, or 120 in other words to cause the board to hang on the sticks from portions which were previously suspended between the sticks. These actions promote efficient and uniform drying of the board; while the successive shifting of the points of support prevents for 125

130

mation of undesirable bends or ruffles in the board and checking of its coated surface.

A heating system for the drying room is represented by a pair of overhead longitudinal hot air ducts 31 having slots 32 in their under sides for blowing heated air upon or toward the upper or coated side of the board, and a number of nozzles 33 in the floor of the room for blowing heated air

10 against the under or uncoated side of the board. In Fig. 1, manifolds for supplying the hot air to the overhead ducts and bottom nozzles are respectively indicated at 34 and 35, these manifolds being connected 15 with a suitable blowing apparatus 36 which may be supplied with hot air from any suitable source; or if preferred air may be heated in the blowing apparatus by a steam pipe coil or otherwise.

20 In drying coated board, it is desirable to subject the board to a gentle and gradual preliminary drying, without exposure of its coated surface to direct action of heat currents, and then to submit the board to a 25 more pronounced drying action in the presence of heat currents directed toward its coated side. By this treatment there is obtained an advantageous preliminary evaporation of moisture and seasoning of the 30 body of the board, and its coating acquires a setting and consistency adapting it to withstand the ensuing more severe drying action.

It will be observed by reference to Fig. 1, 35 that the heating system of the illustrative room is so arranged that the hanging festoons of board are conveyed a considerable distance beyond the receiving end of the room before coming within the range of 40 the bottom hot air nozzles 33, and are conveyed a further considerable distance before coming within the range of the overhead hot air ducts 31; and that the festoons are within the range of both the overhead and underneath heat blasts for a limited distance, 45 after which the drying of the board is continued by the overhead blasts. The specific arrangement shown is such that the festoons first encounter the action of the 50 underneath blasts while conveyed in comparatively distended condition by the first set of longitudinal carrier chains 10, and are subsequently acted upon by said blasts while conveyed in closer folded condition by the 55 carrier chains 11.

This arrangement provides in the drying room a region of preliminary drying, the action of which progresses in two general stages and in several steps. First, the 60 freshly coated board is conveyed with its festoons fairly distended or spread through a substantial distance without submission to drying influence other than the relatively quiescent and temperate atmosphere of the 65 room, accomplishing a gentle initial drying

and setting of the coated surface of the board. Then the festoons come within the range of the underneath heat currents, blowing upwardly against the under or uncoated side of the board and into the spaces between 70 the festoons, warming the body of the board and further advancing the drying. This stage of treatment, commencing while the festoons are moving in relatively distended condition, continues in the illustrative room while the festoons are more slowly moved in contracted condition by the carrier chains 11, during which step there is a relatively greater quantity of the board maintained for a relatively longer period 80 within the range of the underneath blasts. Thus an effectual progressive drying ensues in advance of exposure of the coated surface of the board to the direct action of impinging heat currents. 85

According to the specific arrangement shown, the festoons are brought within the range of the overhead hot air ducts 31 while conveyed in comparatively contracted condition by the slow running chains 11. As the 90 hanging board is further conveyed along the drying room, by a number of successive sets of carrier chains, it is exposed under varying conditions and differently presented to the currents of heated air discharged by 95 said overhead ducts; and also continues for a certain distance to be exposed to the heated air currents ascending from the floor nozzles 33.

In the regions of the drying room traversed by the slow running sections 11, 13, 15, 17 of the conveying system, extensive accumulations of the board in narrow festoons are maintained, so that the volume 100 of heating medium acting during any given interval in these regions is expended upon a relatively large quantity of material, while given portions of the material are exposed in these regions for relatively prolonged periods. Said regions may be appropriately referred to as zones of protracted drying. In the alternating regions of the fast running conveyor sections 12, 14, 16, the board in expanded or distended condition is exposed for relatively briefer intervals, during which the volume of heating medium acts upon relatively small quantities of the board. Thus the drying action 105 per unit of time per unit area of material is substantially greater than that in the 110 zones of protracted drying. Furthermore the drying effect in the regions of the fast running conveyor sections is promoted by the spreading out of the board, and still further accentuated if the board is run over 115 the overhead shifting rollers in proximity to the overhead air ducts. These regions may accordingly be referred to as zones of accelerated drying. 120

By changing the points of suspension of 125

the board, involving reformation of the festoons, the board is differently exposed in successive drying stages, bringing portions which formed lower or intermediate lengths 5 of the festoons in one stage into position for presentation as the upper portions of the festoons in a subsequent stage. Thus different portions of the board are variously exposed to the action of the heat currents 10 in successive drying stages, and the drying action of certain stages complements the drying action of other stages, in addition to continually advancing the degree of dryness of the board. By appropriately re- 15 forming the festoons or effecting appropriate longitudinal shifting of the board a sufficient number of times, the board may be dried substantially uniformly throughout its length.

20 As the board moves rapidly over an overhead shifting roller, its coated surface is uniformly subjected to the action of the hot air blasts in close proximity to the ducts 31, as will be apparent from Fig. 4. This 25 again contributes to efficient and uniform drying. It may however be unnecessary or undesirable in some cases, depending upon the character of the board under treatment and to nature and thickness of the applied 30 coating, to run the board over all the overhead rollers, or to expose its coated surface to close action of the hot air blasts in every zone of accelerated drying, and especially the first such zone. For instance, in some 35 cases the liquid coating may be in too fresh or wet a condition for close exposure to hot air blasts while in the region of the drying room traversed by the chains 12; and in the case of board coated with a thin or quickly 40 drying composition close exposure to the hot air currents in all of the zones of accelerated drying might result in too severe or sudden drying, rendering it expedient to carry the board under one or more of the overhead 45 rollers, or to effect the shifting without such close exposure. For instance, the bottom discharge slots of the overhead ducts may be closed at these portions overlying a roller, so as to permit running the board over such 50 roller for shifting purposes without accompanying severe drying treatment.

With the heating arrangement shown, the board undergoes a period of drying in a medium discharging against its uncoated 55 side, overlapping with a period of drying by a medium discharging toward the coated side of the board. The overlapping interval, in which the board is simultaneously exposed to the action of both the descending 60 and ascending currents of heated air, represents a period of relatively pronounced drying which in this instance occurs in successive steps or stages in the region of the 65 drying room traversed in part by the slow running chains 11, the fast running chains

12, and in part the slow running chains 13. By thus submitting the board under varying conditions to the conjoint action of the ascending and descending currents of heated air, after the period of progressive preliminary drying heretofore described, the board is brought to a condition in which it is adequately responsive to the succeeding stages of drying action, which in this instance are continued by the descending currents of 75 heated air upon the coated side of the board until and, if desired, during the accumulation of the board in the delivery end of the 80 drying room.

The operations described provide a 85 method by which coated paper board is advantageously dried by progressive steps or stages of drying action of different kinds and effects, including recurrent heat treatments under varying conditions in the 90 presentation of the board thereto, for obtaining efficient and substantially uniform drying in the time interval between the coating and finishing of the board. By this method a product thoroughly and uniformly dried and substantially free of flaws may be obtained.

From an accumulation of the dried board hanging in the delivery end of the apparatus, either on the chains 17 or a succeeding 95 set of chains or supporting means associated therewith, the board may be continuously withdrawn for calendering or finishing its coated surface and subdividing the finished product into cut sheets.

As the board runs from the drying room, it may be exposed to the action of hot air blasts discharged from suitable pipes, one of which is shown at 38 in Fig. 2, for the purpose of additional or super-drying action, or to heat the coated surface advantageously for a calendering or finishing operation.

We claim:

1. A drying method characterized by projecting currents of drying medium transversely of a drying enclosure; passing the web undergoing treatment through said currents; subjecting the web to a preliminary drying and seasoning action by said medium in a relatively quiescent state; and subsequently subjecting the web to the moving currents of drying medium under varying conditions providing drying treatments of different effects including recurrent treatments upon differently presented portions of the web.

2. A drying method characterized by exposing the web under treatment in undulating condition to a drying medium in a relatively quiescent and temperate state; and subsequently maintaining said undulating web for a relatively prolonged period in currents of said medium impinging on the web, including successive periods of action

- of said currents upon opposite sides of the web; and successively varying the undulating condition of the web while undergoing drying action by said impinging currents.
5. 3. A drying method characterized by exposing the web in undulating formation and while successively expanding and contracting the undulations to drying action by heat currents moving transversely of the web.
10. 4. A drying method characterized by preliminarily drying the web under treatment in a relatively quiescent and temperate atmosphere and subsequently exposing the web to heat currents under such varying conditions as to provide periods of protracted drying alternating with intervals of accelerated drying.
20. 5. A drying method characterized by maintaining undulations of continuous material moving through a plurality of zones of drying action, including a first zone of gentle drying, a succeeding zone of drying by action of heat currents against one side of the material, and succeeding zones of drying by action of heat currents first upon both sides of the material and then upon the opposite side from that first submitted to said heat currents.
30. 6. A drying method characterized by subjecting the web under treatment to a gentle initial drying in a quiescent atmosphere and subsequently exposing said web to drying action in alternating protracted and accelerated stages in heat currents directed against the web.
40. 7. A drying method characterized by exposing a coated web to progressive stages of drying action without exposure of its coated surface to direct action of heat currents and then progressively drying said web by heat currents directed against said coated surface.
45. 8. A drying method characterized by exposing a web having a coating applied to a selected side thereof to a period of drying action in heat currents discharging against the uncoated side of the web and an overlapping period of drying action in heat cur-
- rents discharging upon the coated side of the web.
9. A drying method characterized by exposing the web under treatment in various conditions to successive stages of drying action including stages of treatment by heat currents acting against one side of the web overlapping with a succeeding period of treatment in heat currents acting upon the opposite side.
10. A drying method characterized by maintaining the web undergoing drying action in undulating formation and repeatedly contracting and expanding the undulations.
11. A drying method characterized by maintaining the web undergoing drying action in undulating formation while successively contracting and expanding the undulations and reforming the undulations.
12. A drying method characterized by exposing a coated web under various conditions to successive stages of drying action by heat currents acting first upon the uncoated side of the web and subsequently for a relatively prolonged period acting upon the coated side.
13. A drying method characterized by maintaining an undulating formation of continuous material and successively reforming the undulations while continuously exposing said material to drying action.
14. A drying method characterized by subjecting a coated web to progressive stages of drying action without exposure of its coated surface to direct action of heat currents and subsequently exposing said web to drying action in alternating protracted and accelerated stages in heat currents directed against the coated surface of the web.
15. A drying method characterized by progressively drying a coated web and blowing heated air upon the coated surface of the dried web as it emerges from the drying operation.

In testimony whereof, we have signed our names to this specification.

CHARLES C. COLBERT.
GEORGE E. PRESTON.
